CLAIM

I claim the ornamental design for a padded shoulder sling strap for cordless tools, as shown and described.

DESCRIPTION

FIG. 1 is a perspective view of a padded shoulder sling strap for cordless tools showing my new design;

FIG. 2 is a side elevational view thereof, the opposite side elevational view being a mirror image thereof

FIG. 3 is an end elevational view thereof;

FIG. 4 is an elevational view of the opposite end thereof;

FIG. 5 is a bottom plan view thereof; and

FIG. 6 is a top plan view thereof; and,

FIG. 7 is a reduced perspective view showing the padded shoulder sling strap for cordless tools in use; the broken lines show environmental structure for illustrative purposes only and form no part of the claimed design.
